(57) **CLAIM**

The ornamental design for an implement for food preparation, as shown and described.

DESCRIPTION

FIG. 1 is a front view of a first embodiment of an implement for food preparation showing my new design;

FIG. 2 is a top view thereof;

FIG. 3 is a rear view thereof;

FIG. 4 is a right side view thereof, the left side being a mirror image of the right side;

FIG. 5 is a perspective view thereof opened in a first configuration;

FIG. 6 is a perspective view thereof opened in a second configuration;

FIG. 7 is a front view of a second embodiment of an implement for food preparation showing my design;

FIG. 8 is top view thereof;

FIG. 9 is a rear view thereof;

FIG. 10 is a right side view thereof, the left side being a mirror image of the right side;

FIG. 11 is a perspective view of the second embodiment opened in a first configuration; and,

FIG. 12 is a perspective view of the second embodiment opened in a second configuration.
